US00D879545S

(12) **United States Design Patent** (10) Patent No.: **US D879,545 S**
(45) Date of Patent: **** Mar. 31, 2020**

(54) **STACKABLE COOKWARE**

- (71) Applicant: **E. MISHAN & SONS, INC.**, New York, NY (US)
- (72) Inventor: **Fred Hollinger**, Monroe Township, NJ (US)
- (73) Assignee: **E. MISHAN & SONS, INC.**, New York, NY (US)
- (**) Term: **15 Years**
- (21) Appl. No.: **29/678,430**
- (22) Filed: **Jan. 29, 2019**

(57) **CLAIM**

The ornamental design for a stackable cookware, as shown and described.

DESCRIPTION

FIG. 1 is a front, right, top, perspective view of stackable cookware showing my design therefor;
FIG. 2 is a rear, top, right perspective view thereof;
FIG. 3 is a side elevational view thereof;
FIG. 4 is a front elevational view thereof;
FIG. 5 is a rear elevational view thereof;
FIG. 6 is a top plan view thereof; and,
FIG. 7 is a bottom plan view thereof.
Throughout the drawings, broken lines indicate environment and form no part of the design.

1 Claim, 7 Drawing Sheets

See application file for complete search history.
